UNITED STATES PATENT OFFICE.

JOHN ZIMMERMAN, OF CHICAGO, ILLINOIS, AND FREDERICK L. WHITE, OF WATERBURY, CONNECTICUT; SAID WHITE ASSIGNOR TO SAID ZIMMERMAN.

LAMP FOR GENERATING ACETYLENE GAS.

SPECIFICATION forming part of Letters Patent No. 600,847, dated March 15, 1898.

Application filed June 18, 1897. Serial No. 641,352. (No model.)

To all whom it may concern:

Be it known that we, JOHN ZIMMERMAN, residing at Chicago, in the county of Cook and State of Illinois, and FREDERICK L. WHITE, 5 residing at Waterbury, in the county of New Haven and State of Connecticut, citizens of the United States, have invented certain new and useful Improvements in Lamps for Forming and Burning Acetylene Gas, of which the 10 following is a specification.

The object of our invention is to provide a simple, economical, and efficient lamp for generating and burning acetylene gas; and the 15 invention consists in the features, combinations, and details of construction hereinafter described and claimed.

In the accompanying drawings, Figure 1 represents a vertical sectional elevation of a bicycle-lamp constructed in accordance with 20 our improvements, taken on line 1 of Fig. 2, looking in the direction of the arrow; Fig. 2, a vertical sectional elevation of the same, taken on line 2 of Fig. 1, looking in the direction of the arrow; Fig. 3, a cross-sectional 25 plan view taken on line 3 of Fig. 2, looking in the direction of the arrow; Fig. 4, an enlarged view of the valve-actuating mechanism and other parts hereinafter described; Fig. 5, a side elevation of the tube for delivering gas from the generating to the liquid 30 chamber; Fig. 6, an enlarged plan view of the valve-seat hereinafter described, and Fig. 7 an enlarged view of the valve in the water-chamber shown in the upper part of Figs. 2 35 and 5.

In describing and illustrating our improvements we prefer to describe them in one form as embodied in a bicycle-lamp, though we do not desire to be limited strictly to this type 40 of lamp other than as the elements are set forth in the claims.

In constructing a lamp in accordance with our improvements we make a receptacle A, preferably cylindrical in contour and which 45 is provided with a generating-chamber a, in which a piece of carbid of calcium a' may be inserted for the purpose of decomposing water and forming acetylene gas. To the receptacle A we preferably secure a second part 50 B, also cylindrical in contour, but arranged

at right angles to the plane of the first receptacle and which forms or provides the liquid-holding chamber b. This receptacle is connected with the generating-chamber by means of a curved tube C, which is opened at its lower end c and closed at its upper end by means of a puppet-valve c', so that pressure on the water may be equalized—that is, the pressure of the generating-chamber is allowed to pass into the liquid-chamber. 55

Heretofore in structures of this class where tubes, pipes, or channels have been used to convey gas under pressure to the liquid-holding chamber a check-valve has been used which only operates in one direction—viz., 60 the direction of the liquid-chamber—so that gas may flow therein. This is objectionable, however, in that if the gas overflows into the liquid-chamber at a high pressure it closes the water-feed valve and keeps it closed, thus 65 preventing the normal action of the apparatus. To overcome this difficulty, we easily fit the puppet-valve c' upon its seat, so that it will be tight enough to prevent water which might overflow and pass into the generating-chamber, but easy enough to permit a back-flow of gas whenever necessary to equalize 70 the pressure. This puppet-valve c' is shown in the enlarged view of Fig. 7, in which the tapered valve portion c² is roughened, as 75 shown in the figure, so that the gas may easily pass back or raise the same to feed it into the water-chamber through the opening c³. At the same time the water caused by splashing when contacting this valve cannot flow easily 80 or readily into the generating-chamber. 85

To feed the liquid or water in the desired quantities to the generating-chamber, we provide a partition B', that separates the liquid-chamber from the generating-chamber, with 90 a valve-seat b'. We next provide the upper part of the liquid-chamber with a diaphragm D and secure to it in any convenient manner a valve-rod D', which is provided with a circular ring portion, upper projecting threaded 95 portion d, and lower projecting valve portion d', the operation being such that as the gas under pressure enters the liquid-chamber and exceeds a predetermined pressure the diaphragm is raised and the opening in the valve- 100

seat closed to prevent the flow of water into the generating-chamber.

To regulate the tension on the diaphragm and the predetermined pressure at which the 5 valve shall be closed, we provide a helical coiled spring E and insert it between the upper cap portion E' of the casing and the diaphragm. The upper threaded portion of the valve-rod is provided with an adjusting-nut 10 e and a second adjusting lever-nut e', so that the tension of the spring may be regulated, the lever-nut being of such construction that it may be readily turned to open or close the valve whenever it is desired so to do and prevent the further inflow of water until the lever-nut has been turned to release the same.

It is desirable at all times to be sure that the liquid reaches the carbid. In order to insure this, we provide the base portion of the 20 generating-chamber with a central upper projecting pin a² and the upper portion of the generating-chamber with a funnel F, so that as liquid flows down from the liquid-chamber it will flow down the funnel and pass through 25 the central portion thereof to contact the carbid, thus always insuring, no matter what position the lamp may be in, the feeding of water to one common point. The neck of the funnel is preferably perforated and may be 30 provided with a piece of absorbent material f, such as sponge, to gradually permit the inflow of water and prevent sudden and rapid formations of gas.

In order to embody our improvements in a 35 bicycle-lamp in as economical a manner as possible and make the lamp efficient from a commercial standpoint, we provide the liquid-holding receptacle with a transverse central conical wall G, that forms a portion of the 40 reflector, the end g being cup-shaped in a manner to focus the rays of light, while the front portion is provided with a lens G' for directing the rays of light in the desired manner. The rear part of the reflector is perforated to admit of a burner H being passed 45 therethrough, which burner is provided with a feed-pipe h, leading to the generating-chamber, and with a valve h' to close or open the passage in the burner, as desired.

50 To feed liquid into the liquid-holding chamber, we provide one side of such chamber with a threaded opening in which is fitted a sealing-plug I, which may be removed whenever desirable to furnish such chamber with 55 a supply of water.

In operation the receptacle A is removed from the body of the lamp and a ring of carbid a' placed therein. It is then restored to its original connection with the body of the 60 lamp, and the sealing-plug we remove from the liquid-receptacle. A supply of water is then furnished the annular liquid-chamber and the lever-nut e' turned around once, so as to permit the helical spring to depress the 65 diaphragm, valve-rod, and feed-valve. This furnishes a limited supply of water to the generating-chamber and forms a quantity of

gas which flows through the curved equalizing-tube C into the liquid-chamber above the water, thus equalizing the pressure on 70 the water, raising the diaphragm, and closing the valve until a quantity of the gas is used out of the generating-chamber. When such gas has been used, a quantity of the gas in the liquid-chamber will flow back through 75 the supply-pipe, lowering the pressure in the liquid-holding chamber, so that the diaphragm may again lower and open the liquid-supply valve to furnish water to the generating-chamber, and thereby allow the generation of a fresh supply of gas.

The circular valve-rod, which is passed around the reflector portion, is made hollow and the upper portion provided with a safety 85 puppet-valve having a helical coiled spring 85 k, adjusted by means of a nut, so that when pressure in the generating-chamber exceeds a safety or predetermined point this puppet-valve will open and permit the excess of pressure to escape.

90 While we have described our invention with more or less minuteness as regards details and as being embodied in certain precise forms, we do not desire to be limited thereto unduly any more than is pointed out 95 in the claims. On the contrary, we contemplate all proper changes in form, construction, and arrangement, the omission of parts and substitution of equivalents as circumstances may suggest or render expedient.

100 We claim—

1. In a lamp for generating and burning acetylene and similar gases, the combination of a receptacle provided with a generating-chamber in the lower portion thereof and a 105 liquid-holding chamber above the generating-chamber, a feed pipe or passage connecting the liquid and generating chambers and valve mechanism arranged thereon to permit the passage of gas either way and prevent the 110 flow of water therethrough, substantially as described.

2. In a lamp for generating and burning acetylene and similar gases, the combination of a receptacle provided with a generating-chamber in the lower portion thereof and a liquid-chamber above the same, a partition dividing the chambers and provided with a valve, a diaphragm in the upper portion of the liquid-chamber, a valve-rod connected 115 with the diaphragm and the valve for opening and closing the same, and a pipe or passage connected with the generating and liquid chambers and provided with a valve to permit the flow of gas in large quantities one 120 way and in small quantities the other way and prevent the flow of water therethrough into the generating-chamber, substantially as described.

3. In a lamp for generating and burning 130 acetylene gas, the combination of a receptacle provided with a generating-chamber in the lower portion thereof, a receptacle above the same provided with an annular liquid-cham-

- ber—the inner walls forming the reflectors of the lamp, and means for automatically feeding the water into the generating-chamber, substantially as described.
- 5 4. In a lamp for generating and burning acetylene gas, the combination of a receptacle provided with a generating-chamber in the lower part thereof and an annular liquid-chamber above the same the inner walls of 10 which form a portion of the reflector, a valve in the wall between the generating and liquid chamber, a diaphragm in the annular chamber and connected with the water-valve to actuate the same by the pressure in the liquid-chamber, an adjustable tension-spring for 15 furnishing the desired pressure to the diaphragm, and with the pipe and valve mechanism for furnishing gas under pressure to the liquid-chamber and allowing it to return 20 therethrough, substantially as described.
5. In a portable lamp for forming and burning acetylene gas, the combination of a receptacle having a generating-chamber in the lower portion thereof and an annular liquid-chamber above the same the inner walls of 25 which form a portion of a reflector, a water-feed valve in the partition which separates the chambers, a diaphragm in the upper part 30 of the liquid-chamber, a hollow rod connected with the diaphragm and water-valve to open

and close the same and furnish through its hollow portion communication with the exterior, and a safety-valve in such rod, substantially as described.

35

6. In a lamp for generating and burning acetylene gas, the combination of a receptacle provided with a generating-chamber in the lower portion thereof, a receptacle above the same provided with an annular liquid-chamber—the inner walls forming the reflectors of the lamp, means for automatically feeding the water into the generating-chamber, and a funnel in the generating-chamber interposed between the liquid-feeding valve and 40 lower portion of the chamber to feed the water to one common point, substantially as described.

45

7. In a lamp for generating and burning acetylene gas, the combination of a receptacle provided with a generating-chamber in the lower portion thereof, and a receptacle above the same provided with an annular liquid-chamber—the inner walls of which form a portion of reflectors of the lamp, substantially 50 as described.
